ATOMIZER

Filed Sept. 12, 1930

UNITED STATES PATENT OFFICE

FRANCOIS NAZARE, OF NEW YORK, N. Y., ASSIGNOR TO AROMEL CORPORATION, OF NEW YORK, N. Y., A CORPORATION OF NEW YORK

ATOMIZER

Application filed September 12, 1930. Serial No. 481,397.

My invention relates to a new and improved atomizer.

One of the objects of my invention is to produce a new and improved portable atomizer which can be made in a relatively small size and which can be used for atomizing and dispensing perfume.

Another object of my invention is to provide a simple, compact, and ornamental boudoir device which can be used, instead of the well known bulb-type atomizers which have heretofore been utilized.

Another object of my invention is to provide an atomizer which shall include a small container having compressed gas therein so that it is merely necessary for the user to operate a valve in order to cause the perfume or other liquid to be atomized.

A fourth object is to arrange the compressed gas container in such manner that any danger resulting from excessive high pressure through high temperature imparted to it from the outside or from accidents of a mechanical nature is minimized.

Other objects of my invention will be set forth in the following description and drawing which illustrates a preferred embodiment thereof, it being understood that the above general statement of the objects of my invention is intended merely to generally explain the same and not to limit it in any manner.

Fig. 1 is a vertical sectional view with the operating valve in the closed position.

Fig. 2 is a sectional view on the line 2—2 of Fig. 1.

Fig. 3 is a sectional view on the line 3—3 of Fig. 1.

Fig. 4 is a detail sectional view showing the operating valve in the open position.

The device comprises a container 1 which is made of any suitable metal, and having a bottom 2 which has the shape shown in Fig. 1. The bottom 2 can be connected to the bottom of the container 1 by soldering or any other suitable means. The container 1 can be filled with perfume or any other suitable liquid, and it is provided with an outlet tube 3, and a strainer 4 at the bottom thereof. The bottom of the outlet tube 3 is close to the adjacent surface of the bottom 2.

A bushing 5 is soldered or otherwise suitably secured in a liquid-tight manner, and the interior wall of this bushing 5 is suitably threaded. The top of the bushing 5 projects slightly above the convex top of the body portion 1. A plug 6 is provided with a downwardly projecting externally threaded portion so that it can be connected to the bushing 5, as shown in Fig. 1. A sealing gasket G is provided in order to provide a gas-tight and liquid-tight fit. The gasket is located in an under-cut groove, so that it is not visible when the parts of the device are assembled, as the gasket would detract from the ornamental appearance of the device. The plug 6 is provided with a holding cylinder 7 which can be connected thereto by means of soldering, a drive fit or any other suitable means. The outlet tube 3 is also connected to the interior of the plug 6 by means of soldering or any other suitable means. However, I prefer to provide a recess in a suitable portion of the interior wall of the plug 6 in which the corresponding part of the tube 3 can be located, so that its upright branch does not project beyond the corresponding part of the interior surface of the plug 6. Hence, when the cylinder 7 is secured in position, it also serves to retain the tube 3 in position.

The holding member 7 is made of suitable resilient metal, and it is provided with a plurality of slots 8 so that it is sufficiently resilient in order to retain the cylinder 9, in which the compressed gas, such as carbon dioxide or other suitable inert gas, is contained. This carbon dioxide is contained under high pressure, as high as two hundred and fifty pounds per square inch. While I do not wish to exclude the use of compressed air, I prefer to use an inert gas which is free from oxygen.

Thus the fourth object, as stated, is accomplished. The high pressure cylinder is placed in a safe and protected position. Undue temperature influences, as heat from some nearby electric heater or alcohol lamp or even sunrays, which might raise the pressure inside the cylinder through heat expansion of the gas to a dangerous degree, cannot

reach it, moreover the liquid surrounding it, has a cooling effect upon the gas, and as the whole apparatus thus becomes more compact, and less top-heavy, the danger of accident, by knocking it over, is greatly lessened.

5 The container 9 is placed within the member 7, before the plug 6 is inserted into the position shown in Fig. 1. The plug 6 is provided with a pin 10 which is made of any 10 suitable hard metal, the point of this pin being made tapered, as shown in Fig. 4. This pin 10 has a threaded upper portion which is retained in a suitably threaded recess of the plug 6.

15 When the container 9 is put into position, it is provided with a closure member 11 which rests against the point of the pin 10. When the plug 6 is screwed into the bushing 5, the bottom of the container 9 rests against the 20 bottom 2 of the device, so that the container 9 cannot descend. Hence, the pin 10 ruptures the seal 11, so that the compressed gas can escape into the interior of the member 1, a slot 10a being provided in the pointed end 25 of the pin 10, in order to permit the escape of the gas.

Hence, the perfume or other liquid within the device tends to escape through the outlet tube 3, and through the outlet channel 12 of 30 the plug.

The upper end of the outlet opening 12 is 35 closed by a valve 14 having a gasket 15. The valve 14 is of cylindrical shape, and it fits over a correspondingly shaped projection 14a of the plug 6. The valve 14 is kept in the lower or closing position which is illustrated in Fig. 1, by means of a compression spring 16. The bottom of the compression spring 16 bears against a shoulder or flange F of 40 the valve 14. The compression spring 16 is held in position by means of a cap 17 whose lower end is internally threaded so as to be retained upon a threaded extension 17a of the plug 6. The projection 17a is provided with 45 a slot 17b. The operating handle 20 passes through the slot 17b. The flange F against which the bottom of the compression spring 16 bears, is also provided with a tooth Fa which fits into the top of said slot 17b, so that 50 the valve 14 can move up and down, but it is prevented from turning.

The handle 20 is provided with a yoke 20a which fits the interior surface of the projection 17a of the plug 6, thus providing a pivot-like connection. Hence, when the handle 20 is depressed, its yoke 20a raises the 55 valve 14 against the force of the spring 16.

The perfume or other liquid is thereupon 60 free to issue from the outlet opening 14b of the valve 14, this outlet being upwardly inclined, as shown in Fig. 4, so that the perfume or other liquid is upwardly sprayed.

The plug is also provided with a relatively narrow channel 21 so that a small current 65 of gas can escape from the receptacle and

move across the upper end of the outlet channel 12, in order to spray or atomize the liquid which would otherwise issue in the form of a fine spray. Although this fine stream would be broken up to some extent, a much finer 70 or more effective spray is secured by utilizing the gas outlet channel 21, so that a thorough mixing of fluid and gas particles is effected, before the spray issues from the orifice 14b.

The plug is provided with a packing 30 75 which is held in place by a nut 31, so that the valve 14 moves up and down in a gas-tight and liquid-tight manner.

The improved device is especially advantageous in dispensing a perfume, because 80 the perfume is maintained free from contact with air, since the parts are hermetically sealed and the interior of the container 1 is filled with an inert gas.

The parts of the device may be made of any 85 suitable metal which will not be affected by the perfume extract, toilet water, or the like. Likewise, the device can be made in any desired ornamental shape and its exterior can 90 be suitably decorated.

Perfume extracts consist essentially of concentrated alcohol in which the perfume ingredients such as various essential oils and the like, are dissolved. These perfumes are very delicate and they are easily affected by oxidation. Hence, perfumes are always sold in 95 tightly sealed bottles which are usually provided with ground glass stoppers in order to produce an air-tight seal. However, when a perfume is put into an atomizer of the ordinary bulb type, it necessarily comes into free contact with air, so that the quality of the perfume is injured. By providing an air-tight atomizer and by forcing the perfume out of the atomizer by means of an inert gas, the 100 quality of the perfume is preserved.

For convenience, I have described the device as being held in the upright position, but of course the device could be held in any desired position. Likewise, it would not be departing from the invention if the plug were inserted through a side of the device instead of being inserted through the top of the device, in which event the vessel 9 would be forced against the side wall of the container 1, instead of being forced against the bottom of 115 the container 1.

I have shown a preferred embodiment of my invention, but it is clear that numerous changes and omissions can be made without departing from its spirit.

I claim:

1. An atomizer comprising a container portion having an opening therein, a plug removably inserted in said opening, a retainer connected with the inside portion of said plug and adapted to hold a sealed vessel which contains a gas under pressure, a pin connected to said plug and adapted to rupture the seal of said vessel before the plug is fully 120 125 130

inserted, an outlet tube connected to said plug, said outlet tube having its outlet end connected to a channel in said plug, and its inlet end at the bottom part of the container, another channel located in said plug and communicating with the interior of said container, a common discharge orifice for both said channels and a valve adapted to control said channels.

10 2. An atomizer comprising a container portion having an opening therein, a plug removably inserted in said opening, a retainer connected with the inside portion of said plug and adapted to hold a sealed vessel which contains a gas under pressure in the interior of said container portion, a pin connected to said plug and adapted to rupture the seal of said vessel before the plug is fully inserted, an outlet tube connected to said plug, said outlet tube having its outlet end connected to a channel in said plug, and its inlet end at the bottom part of the container, another channel located in said plug and communicating with the interior of said container, and a valve adapted to control said channels, said channels extending to the top of the plug, and said valve comprising a cap-shaped member having a lateral outlet forming a common discharge orifice for both said channels.

3. An atomizer comprising a container portion having an opening, a plug located in said opening, an outlet tube vertically supported in a recess of said plug, said outlet tube extending towards the bottom part of the container portion and having a lateral bend which communicates with an outlet channel located in said plug, said outlet channel extending to the outer end of said plug, a second outlet channel in said plug which also extends to its outer end and communicates with the interior of the container, a hollow retainer connected to the inner end of said plug and adapted to retain a sealed vessel which contains a gas under pressure, a pin connected to the inner end of said plug and adapted to rupture the seal of said vessel when the plug is being inserted, a cap-shaped valve slidably mounted upon the outer end of said plug and having a flange, an outer cap member connected to the outer end of said plug, a spring located between said cap-valve, and said outer cap member and adapted to press against said flange to hold said valve in closing position, said valve having a lateral outlet, said valve having means adapted to prevent the same from turning, and an operating handle extending through said outer cap and adapted to move said valve outwardly against the force of the spring.

4. An atomizer, comprising a container for the liquid to be atomized, a plug removably inserted into an opening of said container, a vessel containing gas under pressure and supported by the plug inside of said contain-

er, a mechanical means whereby the compressed gas contained in said vessel can communicate with the interior of said container so that the liquid is subjected to the pressure of said gas, a channel traversing said plug, and an outlet tube for the liquid extending toward a bottom part of the container communicating with said channel, another channel traversing said plug and communicating with the gas under pressure in said container, a cap-shaped valve slidably mounted upon the outer end of said plug, said valve having a lateral outlet, so located that it is closed when the valve is seated upon the plug and it is open when the valve is raised, and resilient leverage means, so that said valve can be temporarily raised, forming a chamber over the plug in which the issuing particles of compressed gas and liquid are mixed before they are driven through said lateral outlet.

In testimony whereof I affix my signature.
